LAND, GLASGOW, SCOTLAND.

STEP-BY-STEP ELECTRICAL TRANSMITTING AND RECEIVING APPARATUS.

1,147,359.

Specification of Letters Patent. Patented July 20, 1915.

Application filed November 30, 1914. Serial No. 874,882.

To all whom it may concern:

Be it known that we, ARCHIBALD BARR, WILLIAM STROUD, and JAMES WEIR FRENCH, subjects of the King of Great Britain and Ireland, and all of Caxton street, Anniesland, Glasgow, Scotland, have invented new and useful Improvements in Step-by-Step Electrical Transmitting and Receiving Apparatus, of which the following is a specification.

This invention relates to improvements in apparatus for the communication of indications electrically, on the step-by-step system, from a transmitting station to a receiving station, and has for its special object the provision of a transmitter that operates a receiver forward and backward, while the transmitter is moved continuously in one direction, the reversal of motion of the receiver taking place at any desired position or at each of a number of positions of the transmitter, for example, at a position corresponding to a neutral or to a maximum or minimum indication or at each of two such positions. In the operation of apparatus according to this invention as will hereafter be understood, reversal in the direction of motion of the transmitter will in all cases be simultaneously accompanied by a reversal in the direction of motion of the receiver, so that a reversal of the receiver takes place whenever there is a reversal of the transmitter as well as at the desired position or positions when the transmitter undergoes no reversal.

The improved system is especially applicable for such purposes as the indication of "bearings" rising, say, from "0° starboard" to $179\frac{1}{2}^{\circ}$, then to 180° and passing continuously to " $179\frac{1}{2}^{\circ}$ port" and on to " 1° port", " 0° port", " 1° starboard," etc., or for the indication of helm positions, say, passing from "starboard 1° " through 0° to "port 1° " and so on, by a reversal of the direction of rotation of the receiver at the appropriate times without a reversal of the direction of motion of the transmitter.

The transmitter and receiver may be of the general lines of those described in United States Patent No. 1009013, dated 14th November, 1911, granted to Archibald Barr and William Stroud, two of the present applicants, (or other types operating in a more

or less analogous manner.) In the case of a receiver operated by the successive energization of three electro-magnets, which we may refer to as 1, 2 and 3, energized in the order 1, 2, 3, for one direction of motion and in the order 3, 2, 1, for the other direction, the reversal of the direction of motion of the receiver may be accomplished by an interchange of two of the circuits between the transmitter and the receiver. Suitable means for this purpose may be constructed by the addition to a transmitter, such as that described in United States Patent No. 1009013 of 1911, Figures 9, 10, 11 and 12, of a reversing switch operated at the appropriate time, which interchanges the circuits to two of the electro-magnets. Thus suppose we require to operate a bearings receiver continuously to indicate bearings rising from 0° to 180° by 1° steps, and passing continuously downward again in readings to 0° and again rising for one direction of motion of the transmitter. In this case suppose that in rising from 0° to 180° the order of action of the magnets is 1, 2, 3, 1, 2, etc., and that when the reading is 180° the magnet 3 is energized. If now the reversing switch is operated so as to interchange the connections of the circuits to magnets 1 and 2, when the reading is 180° the next magnet to be energized will be 2 instead of 1, and the order of action will now be 3, 2, 1, 3, 2, etc., so that the receiver will move backward for the same direction of motion of the transmitter. When passing through 0° the interchange is again made, so that the readings are again caused to increase. In some cases we energize the magnets in the order 1, 1 and 2, 2, 2 and 3, 3, 3 and 1, and so on. In this case the reversal can be performed in like manner if it is effected when only one magnet (say No. 3) is energized. In this case when the reading is $179\frac{1}{2}^{\circ}$, say, the magnet 2 is energized, when 2 and 3 are energized the reading will be $179\frac{1}{2}^{\circ}$, then 180° when 3 is energized, and if 1 and 2 are now interchanged the next step forward of the transmitter energizes 3 and 2, which brings the receiver back to $179\frac{1}{2}^{\circ}$ and so on. The switch used for effecting the reversal may be operated through a carrying mechanism actuated by the transmitter, so that the switch remains at rest until the appropriate

time. Further, simultaneously with the operation of the reversing switch, we may operate means for denoting the change from one group indication to another, in the case of bearings say from starboard to port. This, for example, may be effected by providing a switch arranged to close or open a circuit to an electro-magnet operating a shutter, which denotes, say, starboard when the magnet is energized and port when the circuit is broken. Thus for a continuous forward motion of the transmitter the receiver may be caused to indicate "179 $\frac{1}{2}$ ° starboard", "179 $\frac{1}{2}$ ° starboard", "180° starboard", and the next step of the transmitter causes the indication to change to "port 179 $\frac{1}{2}$ °", "179 $\frac{1}{2}$ °", etc. The operation of the means denoting the change of the group indication and of the switch for reversing the direction of motion of the receiver may again be effected when the 0° indication is passed through. If, in connection with the counter-mechanism provided to indicate the number of steps made by the receiver, stops are provided for the maximum and minimum indications, it will be clear that if a receiver is originally out of step with the transmitter after passing through the maximum and minimum positions, the transmitter and receiver will be in accord, because if the receiver is reading higher (or lower) than the transmitter it will be stopped at the maximum (or minimum) indication until the transmitter is at its maximum (or minimum) indication. Transmitters and receivers appropriate for the indication of helm positions and many other purposes may be made on a similar plan.

In the annexed drawing, Fig. 1 shows diagrammatically the general arrangement of one form of carrying out the present invention, and Fig. 2 shows in greater detail how the transmitting portion may be arranged, and Fig. 3 shows a developed detail of part of Fig. 1.

In Fig. 1 the transmitter is shown on the left and a receiver on the right. 4 is the working handle which through the spur wheel 5 drives the two spur wheels 6 and 7. Upon the shaft of 6 is a commutator 8, of the type described in the specification of United States Patent No. 1009013 of 1911. This commutator consists of a suitable conducting portion 9 mounted upon an insulating drum 10. The left hand portion of the conductor 9 forms a continuous ring, upon which the brush 11 connected with one of the main leads (say the +) presses. As shown in Fig. 1, the brush 1 is connected to the + lead, but if the commutator is rotated in the direction of the arrow the successive contacts made will be to the brushes 1, 2, 3, in the order 1, 1+2, 2, 2+3, 3, 3+1, etc. Further explanation of this part of the mechanism is unnecessary as the arrangement has

already been described in detail in the aforesaid specification of United States Patent No. 1009013 of 1911. As the handle 4 is turned it drives the spur wheel 7 and the disk or drum 12 which are both fixed to the same shaft 13. 12 forms the first of a series of carry-over drums 14, 16, 18 (see also Fig. 2) which are constructed and arranged in a known manner so as to impart one step to a final wheel 19 at each completion of a definite number of turns in one direction of the handle 4. The final wheel at other times remains stationary. The final wheel 19 of the carry-over mechanism is geared to the reversing switch drum 20 through the spur wheels 21 and 22. Upon the drum 20 are two sets of contact pieces 23, 24 and 25, 26 (the latter contact pieces being shown developed in Fig. 3). Starting from the position shown in Fig. 1, the + current flow through brush 11 to brush 1, thence to brush 41 on the reversing switch, through the contact piece 23 to the brush 31 and from there to the element 51 of the receiver. If the commutator 10 is rotated till brush 2 makes contact as well as brush 1, then current will also flow through brush 42, through the contact piece 24 to the brush 32 and receiver element 52; thus both 51 and 52 will be magnetized. After slight further rotation of 10 contact at 1 will be broken, that at 2 will only be made and therefore the receiver element 52 will alone be magnetized. It will further be seen from the connections that whenever brush 3 is connected to brush 11 element 53 will always be magnetized. We shall now consider what happens when we reach the maximum or minimum indication while we still rotate drum 10 in the same sense as before. At this maximum or minimum position the final wheel 19 of the carry-over mechanism is moved through a whole step, say one fifth of a revolution. The spur-gearing 21, 22, is such that this step corresponds to half a revolution of the drum 20, after which the brushes 41 and 32 are brought into contact with the piece 26 and the brushes 31 and 42 with 25. Thus in this position 41 and 32 are connected and 42 and 31. The + current from 1 now flows via 41 through the piece 26 to 32 and thence to 52, while the current from 2 flows via 42 through the piece 25 to 31, and thence to 51, thus interchanging the connections of two of the electro-magnets of the receiver and thereby reversing the direction of rotation. Thus as the drum 10 is continuously rotated in one and the same direction, the receiver will move forward until the carry-over arrangement between 18 and 19 causes the drum 20 to be turned through half a revolution after which it will work backward until 20 is again turned through half a revolution when it will work forward once more and

so on. Upon the drum 20 may be provided an extra conducting contact piece 27 of the shape shown and two brushes 28 and 29. In the position shown 29 is in contact with an insulating portion of the drum 20 and no current passes from 28 to 29, but when 20 turns through half a revolution 28 and 29 will be connected and a current will flow through the coil 30 which can be used to operate, for example, a spring controlled shutter at the receiver, so that when no current flows the word "Starboard" (say) is shown, but as soon as the current passes the shutter is operated hiding the previous signal and exhibiting the word "Port".

Fig. 2 shows in greater detail the carry-over mechanism for working the drum 20 in the maximum and minimum positions. In this figure the electrical details are in the main omitted as they have already been sufficiently discussed in connection with Fig. 1. As before the handle 4 drives the commutator 8 through the spur wheels 5 and 6 and also the spur wheel 7 of the carry-over mechanism through the spur wheels 5 and 55. 7 is fixed to 12, which by means of a tooth upon 12 carries over 13 through (say) one fifth of a revolution once every complete turn. The motion of 13 is communicated to 14 by spur wheels 63 and 64 in continuous mesh, 63 being fixed to 13, and 64 to 14. In the same manner 14 is arranged to carry over 15 which communicates its motion to 16, and 16 is arranged to carry over 17 which communicates its motion to 18. By this carry-over process we can arrange that once in some specified large number of turns of the handle 4, or commutator 8, the final wheel 19 is turned through (say) one fifth of a revolution. When 19 moves forward a step the drum 20 through the gear wheels 21 and 22 is arranged to be turned through a quarter of a revolution (not through half a revolution as the corresponding parts of Fig. 1 are drawn to indicate) in which case the sets of contacts on the reversing switch 20, Fig. 2, would be duplicated on the circumference. Thus on the drum 20, Fig. 2, there are four sets of contact pieces 23, 24, then 25, 26, then 23, 24, and again 25, 26. In the sectional drawing of Fig. 2 only the first and third of these four sets are shown.

We claim:

1. Electrical transmitting and receiving apparatus working on the step-by-step principle, consisting of a receiver having a number of electro-magnets, a transmitter having means capable of being driven forward and backward for controlling the successive energization of the magnets to operate the receiver in a forward and backward direction, in combination with means which at a specific position of the transmitter operate to so alter the order of energization as to

reverse the direction of operation of the receiver while the direction of drive at the transmitter remains unchanged.

2. Electrical transmitting and receiving apparatus working on the step-by-step principle, consisting of a receiver having a number of electro-magnets, a transmitter having means capable of being driven forward and backward for controlling the successive energization of the magnets to operate the receiver in a forward and backward direction, in combination with means which, at each of a number of specified positions of the transmitter, operate to so alter the order of energization as to reverse the direction of operation of the receiver while the direction of drive of the transmitter remains unchanged.

3. Electrical transmitting and receiving apparatus working on the step-by-step principle, consisting of a receiver provided with a number of electro-magnets having circuit connections adapted to be completed by a transmitter, the transmitter having means capable of being driven forward and backward for controlling the successive energization of the magnets to operate the receiver in a forward and backward direction, in combination with circuit means which at a specific position of the transmitter operate to interchange connections at a time when only one of the magnets is energized while the direction of drive at the transmitter remains unchanged, for the purposes set forth.

4. Electrical transmitting and receiving apparatus working on the step-by-step principle, consisting of a receiver provided with a number of electro-magnets having circuit connections adapted to be completed by a transmitter, the transmitter having means capable of being driven forward and backward for controlling the successive energization of the magnets to operate the receiver in a forward and backward direction, in combination with circuit means which at each of a number of specified positions of the transmitter operate to interchange connections at a time when only one of the magnets is energized while the direction of drive at the transmitter remains unchanged, for the purposes set forth.

5. Electrical transmitting and receiving apparatus working on the step-by-step principle, consisting of a receiver provided with a number of electro-magnets having circuit connections adapted to be completed by a transmitter, the transmitter having means capable of being driven forward and backward for controlling the successive energization of the magnets to operate the receiver in a forward and backward direction, in combination with circuit means which at a specific position of the transmitter operate to interchange certain of the connections at a time when only one of the magnets is

- 5 energized (that magnet being not one of those the connection of which is interchanged) while the direction of drive at the transmitter remains unchanged, for the purposes set forth.
6. Electrical transmitting and receiving apparatus working on the step-by-step principle, consisting of a receiver provided with a number of electro-magnets having circuit 10 connections adapted to be completed by a transmitter, the transmitter having means capable of being driven forward and backward for controlling the successive energization of the magnets to operate the receiver in a forward and backward direction, in combination with circuit means which at each of a number of specified positions of the transmitter operate to interchange certain of the connections at a time when only 15 one of the magnets is energized (that magnet being not one of those the connection of which is interchanged) while the direction of drive at the transmitter remains unchanged, for the purposes set forth.
7. Electrical transmitting and receiving apparatus working on the step-by-step principle, consisting of a receiver having a number of electro-magnets, a transmitter having means capable of being driven forward and 20 backward for controlling the successive energization of the magnets to operate the receiver in a forward and backward direction, in combination with means which at a specific position of the transmitter operate to so alter the order of energization as to 25 reverse the direction of operation of the receiver while the direction of drive at the transmitter remains unchanged, and means for denoting on which side of the specific position the transmitter is operating.
8. Electrical transmitting and receiving apparatus working on the step-by-step principle, consisting of a receiver having a number of electro-magnets, a transmitter having means capable of being driven forward and backward for controlling the successive energization of the magnets to operate the receiver in a forward and backward direction, in combination with means which, at each of a number of specified positions of the transmitter, operate to so alter the order of energization as to reverse the direction of operation of the receiver while the direction of drive of the transmitter remains unchanged; and means for denoting on which side of each of the specified positions the transmitter is operating.
9. Electrical transmitting and receiving apparatus working on the step-by-step principle, consisting of a receiver provided with a number of electro-magnets having circuit 50 connections adapted to be completed by a transmitter, the transmitter having means capable of being driven forward and backward for controlling the successive energiza-
- tion of the magnets to operate the receiver in a forward and backward direction, in combination with circuit means which at a specific position of the transmitter operate to interchange connections at a time when only one of the magnets is energized while the direction of drive at the transmitter remains unchanged, together with means for denoting on which side of the specific position the transmitter is operating, for 55 the purposes set forth.
10. Electrical transmitting and receiving apparatus working on the step-by-step principle, consisting of a receiver provided with a number of electro-magnets having circuit 60 connections adapted to be completed by a transmitter, the transmitter having means capable of being driven forward and backward for controlling the successive energization of the magnets to operate the receiver in a forward and backward direction, in combination with circuit means which at each of a number of specified positions of the transmitter operate to interchange connections at a time when only one of the magnets is energized while the direction of drive at the transmitter remains unchanged, together with means for denoting on which side of each of the specified positions the transmitter is operating, for the purposes 65 set forth.
11. Electrical transmitting and receiving apparatus working on the step-by-step principle, consisting of a receiver provided with three electro-magnets having circuit 70 connections, a transmitter having means capable of being driven forward and backward for controlling the circuits and the successive energization of the magnets to operate the receiver in a forward and backward direction, in combination with circuit means which at a specific position of the transmitter operate to interchange two of the circuit connections at a time when one of the magnets is energized, while the direction of drive at the transmitter remains unchanged.
12. Electrical transmitting and receiving apparatus working on the step-by-step principle, consisting of a receiver provided with three electro-magnets having circuit 75 connections, a transmitter having means capable of being driven forward and backward for controlling the circuits and the successive energization of the magnets to operate the receiver in a forward and backward direction, in combination with circuit means which at a specific position of the transmitter operate to interchange two of the circuit connections at a time when one of the magnets is energized, while the direction of drive at the transmitter remains unchanged, together with an auxiliary electro-magnet having a circuit which is completed or broken by the 80 operation of the circuit means.
13. Electrical transmitting and receiving 85

apparatus working on the step-by-step principle, consisting of a receiver provided with three electro-magnets having circuit connections, a transmitter having means capable of being driven forward and backward for controlling the circuits and the successive energization of the magnets on the 1, 2, 3, principle to operate the receiver in a forward and on the 3, 2, 1, principle in a backward direction, in combination with means for interchanging two of the circuit connections at a time when one of the magnets only is energized while the direction of drive at the transmitter remains unchanged.

14. Electrical transmitting and receiving apparatus working on the step-by-step principle, consisting of a receiver provided with three electro-magnets having circuit connec-

tions, a transmitter having means capable of being driven forward and backward for controlling the circuits for the successive energization of the magnets on the 1, 2, 3, principle to operate the receiver in a forward and on the 3, 2, 1, principle in a backward direction, in combination with means for interchanging two of the circuit connections at a time when one of the magnets only is energized while the direction of drive at the transmitter remains unchanged.
